(57) **CLAIM**

The ornamental design for a handle, as shown and described.

DESCRIPTION

FIG. 1 is a front isometric view of a handle shown with indeterminate length in accordance with the present disclosure;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front isometric view of a second embodiment of a handle shown with indeterminate length in accordance with the present disclosure;

FIG. 9 is a front view thereof;

FIG. 10 is a back view thereof;

FIG. 11 is a left side view thereof;

FIG. 12 is a right side view thereof;

FIG. 13 is a top view thereof;

FIG. 14 is a bottom view thereof;

FIG. 15 is a front isometric view of a third embodiment of a handle shown with indeterminate length in accordance with the present disclosure;

FIG. 16 is a front view thereof;

FIG. 17 is a back view thereof;

FIG. 18 is a left side view thereof;

FIG. 19 is a right side view thereof;

FIG. 20 is a top view thereof; and,

FIG. 21 is a bottom view thereof.

The broken lines shown in the Figures are included for the purpose of illustrating features of the disclosed embodiments and form no part of the claimed design. The handle is shown having a break and any portion of the design not shown in the drawings forms no part of the claimed design.

1 Claim, 14 Drawing Sheets
